UNITED STATES PATENT OFFICE.

ALBIN WARTH, OF STAPLETON, NEW YORK.

CLOTH-CUTTING MACHINE.

SPECIFICATION forming part of Letters Patent No. 380,962, dated April 10, 1888.

Application filed November 12, 1887. Serial No. 254,985. (No model.)

To all whom it may concern:

Be it known that I, ALBIN WARTH, a citizen of the United States, residing at Stapleton, in the county of Richmond and State of New York, have invented new and useful Improvements in Machines for Cutting Textile and other Materials, of which the following is a specification.

This invention relates to certain improvements in machines for cutting textile and other materials of that class which I have described in Letters Patent No. 363,705, dated May 24, 1887, said improvements being pointed out in the following specification and claims, and illustrated in the accompanying drawings, in which—

Figure 1 represents a sectional side view of a cutting-machine. Fig. 2 is a plan or top view of the same. Fig. 3 is a horizontal section in the plane x x , Fig. 1. Fig. 4 is a sectional side view of a modification. Fig. 5 is a plan or top view of the same. Fig. 6 is a vertical section of another modification, the plane of section being indicated by the line x^2 x^2 , Fig. 7. Fig. 7 is a plan or top view of the same. Fig. 8 is a horizontal section in the line z z , Fig. 9, and looking in the direction of the arrow opposite to that line. Fig. 9 is a sectional side view of the upper portion of the machine. Fig. 10 is a horizontal section in the plane y y , Fig. 6. Fig. 11 is a sectional side view of another modification. Fig. 12 is a plan or top view.

Similar letters indicate corresponding parts.

In the drawings, the letter A designates the foot-plate, from which rises a standard or pillar, B, the upper portion of which is round and guided in one of the eyes a , formed on a bracket, O, which is secured to the outer end 40 of an arm, C. A collar, a^* , retains the eye a in position on the pillar. Into the interior of the pillar B is fitted the knife-bar D, the lower portion of which is flat, (see Figs. 3 and 10,) while its upper portion is round, or so formed 45 that it will turn in a round hole.

In the example shown in Figs. 1, 2, and 3 the upper round portion of the knife-bar D is made hollow, so as to reduce its weight, and it is guided in the eye a' of the bracket O, and 50 it extends up through said eye. On its upper end are formed circular grooves b , which engage with a toothed segment, c , formed on the

end of the arm F of a double-armed lever, F G. This lever has its fulcrum on a pivot, d , secured on the arm C, and the inner end of its arm G connects by a rod, H, with the crank I on a shaft, J. This shaft has its bearings in journal-boxes e , secured to the arm C, and on it are mounted the fast and loose pulleys P P' and the fly-wheel W. On the pillar B is firmly secured a handle, R, which serves to guide the cutting mechanism. By turning the pillar B round the knife-bar, a portion of which is flat, as already stated, is compelled to turn also without throwing the circular grooves b out 65 of gear with the toothed segment c on the double-armed lever F G. On the arm G of this double-armed lever is secured a weight, K, to balance the weight of the knife-bar.

In the example shown in Figs. 4 and 5 the 70 foot-plate A, the pillar B, the knife-bar D, the bracket O, and the arm C are the same as the corresponding parts in Figs. 1, 2, and 3; but the double-armed lever F G is made in the form of a bell-crank lever, which engages the 75 knife-bar by means of the toothed segment c and the circular grooves b , Fig. 4, and to which is connected the balance-weight K. The arm G of said double-armed lever connects by the rod H with the crank or eccentric I on the 80 driving-shaft J.

In the example shown in Figs. 6 to 10 the double-armed lever F G is connected to the crank I on the shaft J by the connecting-rod H precisely in the same manner as in the example shown in Figs. 1 and 2, and the double-armed lever engages the knife-bar D; but the means employed for effecting this engagement are different, in order to show that the circular grooves b and toothed segment c (shown in 90 Figs. 1 and 4) are not the only means which can be used to effect this engagement.

On the knife-bar D, Figs. 6 and 9, is fitted a ring, f , in which the knife-bar can freely turn, but which is confined between a fixed 95 shoulder, g , and a collar, h , said collar being adjustable on the knife-bar by a screw-thread. (See Fig. 9.) The arm F of the double-armed lever F G is bifurcated, and the ends of the fork connect by links i with the ring f on the knife-bar D. By imparting to the lever F G an oscillating motion the knife-bar receives a reciprocating motion.

The pillar B, which rises from the foot-plate

A, is guided in the eye *a* of the bracket O, and the lower flat end of the knife-bar D is guided in the pillar B, Fig. 10, the eye *a* being retained on the pillar by the collar *a** in the same manner as in the examples heretofore described; but the handle R, instead of being connected to the pillar B, is transferred above the bracket O, and it is provided with a hub, *j*, which extends through the eye *a'* of said bracket and carries a cog-wheel, *k*, which gears into a pinion, *l*, mounted on the shaft *m*. This shaft has its bearings in lugs *n n*, projecting from the eyes *a a'* of the bracket O, and it carries a second pinion, *o*, which gears into a cog-wheel, *p*, formed on the collar *a**, which is firmly secured to the upper end of the pillar B. The upper end of the knife-bar D is guided in and extends through the hub *j* of the handle R. By this arrangement I am enabled to bring the driving mechanism in direct engagement with the knife-bar and to place the handle R above the arm C, so that said arm does not interfere with the operation of guiding the cutting mechanism, according to the contours of the patterns to be cut, and in order to keep the motion of the cutting mechanism as steady as possible the momentum of the knife-bar is balanced by the weight K.

It will be noticed that in the apparatus described in Patent No. 363,705, above named, the mechanism for imparting motion to the knife-bar engages said knife-bar D by means of a sleeve fitted upon the pillar B. In my present application the sleeve is dispensed with, and the driving mechanism is made to engage the knife-bar directly. At the same time the momentum of the knife-bar is counteracted and balanced by the momentum of the weight K.

In the modification shown in Figs. 11 and 12 I have substituted a single-armed lever, F, for the double-armed lever F G. By referring to these figures it will be observed that all the parts represented therein are precisely the same as those represented in Figs. 6 and 7, with the only exception that the single-armed lever F, Figs. 11 and 12, connects with the crank or eccentric I at a point between its fulcrum *d* and its connection with the knife-bar. From the eye of the lever F extends an arm, G, which carries the balance-weight K.

If it is considered that in my machines the foot-plate A, which supports the cloth to be cut, moves loosely over a table, and that my machines are driven with a speed of from fifteen hundred to two thousand revolutions per minute, the importance of reducing the weight of the moving parts will be readily

understood. In my machines as previously constructed I always employed a knife-bar and a sleeve, to which a reciprocating motion is imparted and which engages the knife-bar. In my present invention the sleeve is dispensed with, and the liability to impart to the foot-plate a jumping motion is materially reduced.

What I claim as new, and desire to secure by Letters Patent, is—

1. The combination, with the movable foot-plate A, the pillar B, and the knife-bar D, fitted into the pillar, of the oscillating lever directly engaging the knife-bar above the foot-plate, and mechanism, substantially as described, for imparting motion to said lever.

2. The combination, with the movable foot-plate A, the pillar B, and the knife-bar D, fitted into the pillar, of the lever F G, directly engaging the knife-bar, the weight K, having a movement in a direction opposite to that of the knife-bar for balancing the weight of the knife-bar, and mechanism, substantially as described, for imparting motion to the double-armed lever.

3. The combination, with the movable foot-plate A, the pillar B, the knife-bar D, fitted into the pillar, and the arm C, of the bracket O, secured to said arm, the eye *a* on said arm for guiding the pillar B, the eye *a'* for guiding the upper portion of the knife-bar D, the oscillating lever having direct engagement with the knife-bar, and mechanism, substantially as described, for imparting motion to the double-armed lever.

4. The combination, with the movable foot-plate A, the pillar B, the knife-bar D, fitted into the pillar, the handle R, and the arm C, of the bracket O, secured to said arm, the eye *a* on said arm for guiding the pillar B, the eye *a'* for guiding the hub of the handle R, the shaft *m*, which is geared together with the hub *j* of the handle, and also with the pillar B, and mechanism, substantially as described, for imparting motion to the knife-bar.

5. The combination, with the movable foot-plate A, the pillar B, and the knife-bar D, fitted into the pillar, of the oscillating lever, the ring *f*, fitted on the knife-bar and connected to said lever, and mechanism, substantially as described, for imparting motion to the lever.

In testimony whereof I have hereunto set my hand and seal in the presence of two subscribing witnesses.
